UNITED STATES PATENT OFFICE.

JOHN BONIFANT, OF ROCKVILLE, MARYLAND.

SHOE-LACING DEVICE.

1,123,077.

Specification of Letters Patent. Patented Dec. 29, 1914.

Application filed March 30, 1914. Serial No. 828,365.

To all whom it may concern:

Be it known that I, JOHN BONIFANT, a citizen of the United States, residing at Rockville, in the county of Montgomery and State of Maryland, have invented new and useful Improvements in Shoe-Lacing Devices, of which the following is a specification.

The invention relates to boots and shoes, and more particularly to that class of devices for use in lacing and securing boots or shoes upon the foot of the wearer.

The primary object of the invention is to provide a simple structure which can be readily applied to boots or shoes and in which it is not necessary to withdraw the usual lacing from the eyelets in the upper of the boot or shoe in order to remove the same from the foot and in which, furthermore, by simply loosening the lacing the boot or shoe can be removed and as readily applied to the foot of the wearer.

In the further disclosure of the invention reference is to be had to the accompanying drawings, constituting a part of this specification, in which similar characters of reference denote corresponding parts in all the views, and in which:

Figure 1 is a fragmentary perspective view of the shoe, showing my device applied thereto; Fig. 2 is a horizontal sectional view taken on the line 2—2 in Fig. 1; and Fig. 3 is a fragmentary perspective view of a modified form of my device.

Referring more particularly to the views, I disclose a shoe 10 having an upper 11, the edges 12 of which it is desired to draw together after the shoe has been applied to the foot of the wearer. To this end, a series of eyelets 13 are arranged in opposed relation adjacent the edges 12 of the upper 11 as shown, and a single lacing 14 is passed through the eyelets 13 as shown, with the ends of the lacing at the upper ends of the upper, the said lacing being so arranged that it will readily slide through the eyelets and having portions between opposed and adjacent eyelets forming opposed loops 15.

A member 16 is provided to connect the opposed loops of the lacing between each pair of adjacent eyelets and the said member consists, more particularly, of a single piece of metal or other material of a flat ribbon-like nature and constituting a body 17 hav-

ing its end bent rearwardly upon itself to 55 form eyelets 18 through which the loops 15 pass.

In assembling the structure mentioned the lacing 14 is first arranged upon the upper 11 as shown to provide the opposed loops 15, 60 with the adjacent lacing passing through the eyelets 13 and then the members 16 are applied to the opposed loops of the lacing, the said member when first applied being flat, after which its ends are bent around the 65 loops 15 as shown, so that the loops can loosely slide through the eyelets formed by the bent ends of the member. Now assuming that the lacing is loose, after the shoe has been applied to the foot of the wearer, it 70 is only necessary to draw up at different portions along the loops of the lacing and then exert a final pull on the free ends of the lacing at the upper end of the upper, thereby drawing the edges 12 of the upper together 75 without necessitating the passing of the lacing through the eyelets after the shoe has been applied and which is usually the case with most shoes now generally worn and which are provided with eyelets. Similarly, when it is desired to remove the shoe 80 from the foot of the wearer, it is only necessary to undo or untie the ends of the lacing at the upper edge of the upper and then by gripping the upper adjacent its edges 12 the 85 same can be spread apart so that the lacing will loosely slide through the members 16 and the eyelets 13 so that the edges of the upper can be spaced sufficiently apart to permit of readily withdrawing the shoe from 90 the foot of the wearer.

In Fig. 3 I disclose a modified form of my device in which instance, instead of providing opposed eyelets 18, I provide opposed pairs of eyelets 19, with the eyelets arranged 95 in pairs along each edge of the upper and with each pair of eyelets in opposed relation to another pair of eyelets along the other edge of the upper, the lacing being adapted to pass downwardly through the first eyelet 100 in each pair and then upwardly through the second eyelet in each pair, so that the portions of the lacing between adjacent pairs of eyelets will form loops 20 similar to the loops 15 to which the members 16 are applied. 105

From the foregoing description it will be apparent that the structures set forth are

simple, and that the lacing and members 16 can be readily applied to various forms and styles of shoes or boots.

The device described is particularly adaptable for use on shoes or boots having what are known as high uppers and which extend upwardly almost to the knee, as in hunting boots and the like.

Having thus described my invention, I 10 claim:

In combination with a lacing for foot gear, said lacing being interlaced on the foot gear, a flat ribbon-like member formed of a single piece of flat metal having its ends 15 bent in the form of eyelets lying on the same

side of the body of said flat ribbon-like member with a portion of the lacing passing through one of the eyelets and the opposed portion of the lacing passing through the other eyelet whereby said flat-ribbon-like 20 member will be carried by opposed similar portions of the lacing and lie between portions of the lacing which engage the foot gear and are interlaced therein.

In testimony whereof I affix my signature 25 in presence of two witnesses.

JOHN BONIFANT.
